UNITED STATES PATENT OFFICE.

ULYSSES S. HUGGINS, OF PITTSBURGH, PENNSYLVANIA.

SAND TOY.

Application filed November 21, 1922. Serial No. 602,434.

To all whom it may concern:

Be it known that I, ULYSSES S. HUGGINS, a citizen of the United States, residing at Pittsburgh, in the county of Allegheny and 5 State of Pennsylvania, have invented certain new and useful Improvements in Sand Toys, of which the following is a specification.

The object of this invention is to provide 10 a new kind of a toy.

Another object if the invention is to provide a toy in which the figure of a man will be operated automatically from an upright to bending position by the weight of 15 sand flowing intermittently from a hopper into a hod and will be restored to an upright position upon the dumping of the hod.

This and other objects of the invention 20 will be illustrated in the drawings, described in the specification and pointed out in the claims at the end thereof.

In the drawings,—

Figure 1 is a side elevation of the toy 25 with the figure of the man in an upright position with the hopper, valve, hod and base shown in section.

Figure 2 is a side elevation showing the 30 figure of the man in the bent position with one of the uprights partly broken away and the valve shown in section.

Figure 3 is a front elevation of the figure 35 of a man with the hod and spout included in the figure.

In the drawings, like reference numerals indicate like parts.

In the drawings, reference numeral 1 indicates the base and 2 indicates a circular flange preferably of tin or other suitable 40 material which with the base forms a pan or tank for catching the sand. Within the pan are fastened two uprights 3 and 4 which at the top support the hopper 5. On the bottom of this hopper is provided a tapered 45 spout 6 having a pin 7 therethrough from which swings the valve 8. This valve is normally in the position shown in Figure 2 and stops the flow of sand from the spout of the hopper. The base has an extension 50 to one side as indicated at 9 on which is rigidly fastened the legs 10 of a man. At

the top of these legs is provided a pivot 11 which supports the body 12 of the man and leaves it free to swing forward between the legs. Below the pivot 11 is a pin 13 which 55 extends between the legs and which is adapted to engage the body at the recess 14 so as to hold the body in the upright position shown in Figure 1. The arms 15 of the man are pivoted to the body on the 60 pin 16 which extends through the body and the arms are connected to the legs by the wire links 17, 18, one of which is provided on each side of the body. These links are fastened to the legs back of and above the 65 holes for the pivot 11. They are fastened to the arms a short distance in front of the pivot pin 16 and the effect of the links is to normally hold the arms in an upward position and cause the arms to swing down as 70 the body is tilted to the position shown in Figure 2.

Between the hands 20 of the man is provided a hod 21 having the bail 22 rigidly fastened thereto. When in the upright 75 position this bail engages the extension 23 on the valve 8 and swings it to the position shown in Figure 1. This uncovers the bottom of the spout and permits the sand to flow into the hod. When enough sand 80 has accumulated to weight the body down at the top, the body and arms swing to the position shown in Figure 2.

It will be understood that the body is 85 so shaped that the part represented by the coat-tail 24 and below the pivot 11, weighs more than the part of the body above it, and this weight is sufficient to return the body from the position shown in Figure 2 after the sand is dumped from the hod and 90 hold it normally in the position shown in Figure 1. For this purpose a block of lead is fastened into the coat-tail at the bottom as indicated at 25.

The operation of the toy is as follows: 95

With the parts in the position shown in Figure 1, sand is poured into the hopper 5 and flows through the spout 6 into the hod 21. When the hod has become filled with sufficient weight of sand it causes the figure 100 to tilt to the position shown in Figure 2 whereupon the sand flows out of the hod

into the pan formed on the base. As soon as the figure is relieved from the weight of the sand the excess weight of the tail will cause the figure to again swing to the upright position. While the figure is in course of swinging down and up the valve 8 swings to the position shown in Figure 2 and stops the flow of sand so that no sand flows except when the hod is under the 10 spout.

I claim:

1. In a sand mill, the combination of a hopper, a spout in the bottom thereof, a valve normally swung under said spout to 15 shut off the flow of sand, a base, a figure of a man below said hopper said figure having legs rigidly supported on said base, forming a standard thereon, a body pivoted on said legs arms pivoted on 20 said body and adapted to swing thereon, links connecting said swinging arms and said stationary legs for normally holding said arms up in a predetermined position and causing the arms to swing relative to 25 the body as the body swings forward on the stationary legs.

2. In a sand mill, the combination of a base, the legs of the figure of a man rigidly supported on the base, a body pivoted on 30 said legs, a coat tail on said body projecting down and out, a pin between the legs below said body forming a stop between said legs, a weight in said tail to over-balance and hold the body against said pin and in line 35 with the legs.

3. In a sand mill, the combination of a base, the legs of the figure of a man rigidly supported on the base, a body pivoted on 40 said legs, a coat tail on said body projecting down and out, a pin between the legs below said body forming a stop between said legs, a weight in said tail to over-balance and hold the body against said pin and in line 45 with the legs, arms pivoted on said body, links between said legs and said arms for normally holding the arms up and causing the arms to swing relative to the body as the body swings forward on the legs.

4. In a sand mill, the combination of a base, the legs of the figure of a man rigidly supported on the base, a body pivoted on 50 said legs, a coat tail on said body projecting down and out, a pin between the legs below said body forming a stop between said legs, a weight in said tail to over-balance and hold the body against said pin and in line 55 with the legs, arms pivoted on said body, links between said legs and said arms for normally holding the arms up and causing the arms to swing relative to the body as the body swings forward on the legs, a hod supported by said arms in an upright position.

5. In a sand mill, the combination of a base, the legs of the figure of a man rigidly supported on the base, a body pivoted on 60

said legs, a coat tail on said body projecting down and out, a pin between the legs below said body forming a stop between said legs, a weight in said tail to over-balance and hold the body against said pin and in line 70 with the legs, arms pivoted on said body, links between said legs and said arms for normally holding the arms up and causing the arms to swing relative to the body as the body swings forward on the legs, a hod supported by said arms in an upright position, a hopper above said hod, a spout thereon discharging a load into the hod, the weight of said load over-balancing the coat tail of the body and causing said body and arms 80 to tilt and dump the hod.

6. In a sand mill, the combination of a base, the legs of the figure of a man rigidly supported on the base, a body pivoted on 85 said legs, a coat tail on said body projecting down and out, a pin between the legs below said body forming a stop between said legs, a weight in said tail to over-balance and hold the body against said pin and in line 90 with the legs, arms pivoted on said body, links between said legs and said arms for normally holding the arms up and causing the arms to swing relative to the body as the body swings forward on the legs, a hod supported by said arms in an upright position, a hopper above said hod, a spout thereon discharging a load into the hod, the weight of said load over-balancing the coat tail of the body and causing said body and arms 95 to tilt and dump the hod, a valve under the spout to close the spout when the body and hod are tilting.

7. In a sand mill, the combination of a base, the legs of the figure of a man rigidly supported on the base, a body pivoted on 100 said legs, a coat tail on said body projecting down and out, a pin between the legs below said body forming a stop between said legs, a weight in said tail to over-balance and hold the body against the pin and in line 105 with the legs, arms pivoted on said body, links between said legs and said arms for normally holding the arms up and causing the arms to swing relative to the body as the body swings forward on the legs, a hod supported by said arms in an upright position, a hopper above said hod, a spout thereon discharging a load into the hod, the weight of said load over-balancing the coat tail of 110 the body and causing said body and arms to tilt and dump the hod, a valve under the spout to close the spout when the body and hod are tilting, means for moving said valve away from the spout when the hod is 115 in position under the spout.

8. In a sandmill, the combination of a hopper, a spout at the bottom of said hopper, a valve normally closing said spout, a figure comprising a pair of stationary up- 120 rights, a lever mounted to swing between 125

said uprights, an arm mounted to swing on said lever and forming an extension therefor, a link connecting said arm with said stationary uprights, said link operating to swing said arm carried by said lever and shorten or lengthen the extension formed by it for said lever, a hod carried on the end of said arm, said hod being adapted to swing with said arm and open said valve when brought into contact therewith. 10
In testimony whereof I affix my signature.

ULYSSES S. HUGGINS.
